2 Claims. (Cl. 340—378)

The present invention relates to electro-mechanical display units by means of which any one of a number of different characters, such as numerals, may be displayed selectively under electrical control. More particularly, the invention is concerned with a unit of this kind having a display screen, a rotary stencil plate bearing the characters within equispaced character spaces, and a single light beam source to project on to the screen the image of whichever of the characters is in the space positioned in alignment with the light beam.

In order to set the stencil plate to the various display positions the invention provides a driving arrangement comprising a permanent magnet rotor and a multi-pole stator having a number of energizing windings equal to half the number of characters such that the required number of different positions of the rotor is obtainable by energization of the windings individually with current of the one polarity or the other.

Display units in accordance with the invention are suited to the requirements of control panels where it is becoming common for a large number of controls and indications to be centralized on a single panel. Thus, if the task of supervision is to be manageable, the various control and indication elements must occupy as little space as possible. Whereas display units in use hitherto have included a cluster of separate lamp bulbs, one for each character, the present unit needs only one and the bulk of the driving arrangement can be accommodated within closer boundaries than the previous bulb cluster on account of the number of windings being only half the number of characters. It is these boundaries of width and height that are important because when once the size of the display has been decided neither of these dimensions should be much greater in order that, on the one hand, the continuity of a multi-character display afforded by several units arranged side by side shall not be broken by large gaps between consecutive characters, and, on the other hand, the unit can be inserted in the free space between lines of other elements.

The unit is preferably of a uniform generally rectangular cross section and accommodated therein in the order given proceeding lengthwise from the display end are: the screen, a subassembly comprising a flat circular stencil plate rotatable about the lengthwise axis and a fixed lens system, a single lamp bulb and mounting therefore, and, finally, the driving arrangement, the rotor of the latter being drivingly connected with the stencil plate by a spindle.

The rotor of the driving arrangement may be caged within formers around which the windings are wound in planes passing through the axis of rotation of the rotor. Alternatively, the stator may have the windings on cores extending parallel to the axis of rotation and present pole faces facing one side of the rotor. If, in this latter case, the stator cores are arranged symmetrically in diametrically opposed pairs, the centers of the poles of the permanent magnet rotor are displaced angularly by an odd multiple of half the pitch of the stator cores.

The invention will be further described with reference to one particular embodiment adapted for use as a train description indicator and which will be described, by way

2

of example, with reference to the accompanying drawings, in which:

FIG. 1 is a plan view partially in section showing one form of a display unit in accordance with our invention.

FIG. 2 is a cross-sectional view taken along line I—I of FIG. 1, to show to better advantage, the configuration of the magnetic rotor incorporated in the display unit embodying our invention.

FIG. 3 is a view also taken along line I—I of FIG. 1 but showing the display unit of our invention mounted in juxtaposed relation with a similar unit to allow the display of a multi-digit number.

FIG. 4 is a cross-sectional view taken along line II—II of FIG. 1 to better illustrate one particular arrangement 15 of a group of cores spaced in angular relation in the display unit embodying our invention.

FIG. 5 is a cross-sectional view taken along line III—III of FIG. 1 to show the information bearing stencil plate.

Similar reference characters refer to similar parts in 20 each of the several views.

Referring now to FIG. 1 of the drawings, the front end of a rectangular section casing 10 is closed by a flat transparent screen 12 with a diffusion layer on its internal surface so that light images projected thereon may be 25 visible over a wide angle of view. Spaced back from the screen there is accommodated a sub-assembly comprising two partitions 14 and 16 with a rotary stencil plate 18 interposed in the space between them. These partitions are perpendicular to the lengthwise axis of the casing and 30 the one nearest the screen 12 provides a bearing 20 for the front end of a spindle 22 on which the stencil plate 18 is fixed, this spindle passing through a hole in the other partition 16.

In the present invention, as shown in FIG. 5, the stencil plate 18 has numeral characters 19 thereon and may have, in addition, other supplementary characters such, for example, as an asterisk 21.

The stencil plate 18 is in the form of a thin flat disc originally of transparent material which is silk-screen printed so as to leave in a peripheral band the shapes of the numeral characters 19 and other necessary characters pervious to incident light, there being in this band twelve equispaced character spaces of which one is unoccupied in the case of the characters being an asterisk 21 and ten numeral characters 19. The unoccupied space is generally designated as 23.

Spaced behind the partitions 14 and 16 is a further partition 24 providing the mounting for a lamp bulb 26. This bulb is eccentrically disposed in relation to the spindle and is aligned with apertures 16a and 14a in the pair of partitions preceding it. In the nearer aperture 16a is a condenser lens 28 by which the light of the lamp bulb is beamed through the character bearing band of the stencil plate 18. In the further aperture 14a is a projector lens 30 to project the resulting light image of the appropriate numeral character 19 or supplementary character on to the screen, at the same time correcting for the eccentricity of the beam in relation to the screen.

Behind the lamp bulb mounting partition follows the 60 driving arrangement which comprises a permanent magnet rotor 32 fixed to spindle 22, which spindle extends through a hole 24a in the lamp bulb partition 24 and is supported at its rear end in a bearing 36 provided by a fixed stator assembly generally designated 38. This assembly 38 has a ring of six cores indicated 40 (FIG. 4) 65 equally spaced in angular relation and disposed about a central core 44 of magnetic material whose function will be described below. Cores 40 are arranged symmetrically in diametrically opposed pairs parallel to the axis of the spindle 22 and present pole faces facing, with an interposed air gap, towards the rearward side or, as shown in

FIG. 1, on the right-hand side of the permanent magnet rotor. On each of the cores is wound a stator winding 46 (FIG. 1) by which each stator core can be separately energized. At the rear end of the unit are suitable terminal pins 48 for plugging into a socket, these pins providing for illumination of the lamp bulb and energization of the separate windings.

As can be seen from FIG. 2, the permanent magnet rotor 32 is slightly cranked or off-set in that the two arms, on an arc covering the shortest distance between them, have the respective pole centers displaced angularly by 180° less half of the pitch of the stator cores, that is to say, by 150° . It should be noted that with this arrangement one or the other of the rotor tips is never over 150° from the farthest stator cores. From any one position to another, therefore, the forces on the rotor are always unbalanced and any movement of the rotor of less than 180° takes place via the shortest route. The tips 32a and 32b of the rotor are extended and bent at right angles so that when the rotor moves toward an energized stator core, the reluctance gradually decreases. When the energized core is actually reached the reluctance suddenly decreases, giving a substantial holding force and precise positioning.

It will be evident that two different positions of the rotor are obtained by energizing any one of the stator windings with current of one polarity or current of the opposite polarity. The return path between the ends of the cores for the magnetic flux is via the rotor 32 and center core 44. Thus, for all possible modes of energizing the six windings individually, twelve positions of the rotor are obtainable. Each such position corresponds by virtue of the spindle connecting the rotor to the stencil plate 18 to the alignment of a different character space with the light beam. Any one of the available characters may therefore be displayed by energizing the appropriate winding with the appropriate polarity. The lamp bulb may burn steadily, or if necessary it may be extinguished momentarily on changing of the display in order that any oscillations of the stencil plate 18 in settling in its fresh position after a large swing may not be apparent on the screen.

Moreover, it will be appreciated that by providing a larger number of stator windings and associated cores, and by modifying the shape of the permanent magnet rotor in accordance with the change in pitch brought about by the increased number of cores, an arrangement allowing for the display of a greater number of characters may be obtained.

From its front to rear ends the casing is of the same rectangular section, slightly higher than wide, and therefore a bank of units may be assembled side by side in a panel for the purpose of displaying multi-digit numbers, as we have shown in FIG. 3. In this case, a masking arrangement at the screen may be provided to prevent adjacent digits from being displayed.

Although we have herein shown and described only one form of data display indicator embodying our invention, it will be understood that various changes and modifications may be made therein within the scope of the appended claims without departing from the spirit and scope of our invention.

Having thus described our invention, what we claim is:

1. A data display indicator including a case provided

at one end with a viewing screen, a rotary disc having character information thereon located within said case, means for projecting the image of at least one of the characters on said disc onto said screen, shaft means concentric with said disc for supporting it, a permanent magnet rotor rigidly mounted on said shaft to effect synchronous movement of the rotor and said disc, a plurality of core members arranged circumferentially about and parallel to the axis of said shaft means and presenting pole faces facing the side of said rotor opposite that facing said disc, said pole faces being angularly displaced from an adjacent pole face by the same pitch, a winding on each of said core members for selectively polarizing said core members individually, the centers of the rotor poles being displaced angularly by a multiple of half the pitch of said pole faces, means enclosed by said core members between their ends for completing a magnetic flux path between the ends of a core member when said core member is polarized, said permanent magnet rotor having two distinct positions for each polarity of each one of said core members, said permanent magnet rotor moving into attracted magnetic relation with said core member in accordance with the polarization of said core members to cause the projection onto said screen of a character determined by the position of said rotor.

2. A data display indicator comprising a rotary stencil plate bearing a plurality of characters within equispaced character spaces, a light source to project the image of whichever of the characters is in the space positioned in alignment with the light source, a spindle on which said stencil plate is fixed, a permanent magnet rotor mounted on said spindle concentric with said stencil plate, a plurality of core members presenting pole faces facing the side of said rotor opposite that facing said stencil plate, said pole members circumferentially arranged parallel to and symmetrically around the axis of said spindle, a central core enclosed by said core members and extending substantially between the ends of said core members along said axis, a winding on each of said core members for selectively polarizing said core members individually, whereby the oppositely poled arm of said rotor is attracted into magnetic relation with the polarized core member, the tips of said rotor being bent toward the pole faces of said core members so that when said rotor moves toward the polarized core member the reluctance gradually decreases and then suddenly decreases when said polarized core member is actually reached.
